RAILWAY TRACK BOND

Harry H. Seifert, Troy, N. Y.

Application March 8, 1946, Serial No. 652,970

15. Claims. (Cl. 238—14.13)

1

This invention relates to bonds used for electrically connecting the adjoining rails of a railroad track in forming the track circuits of a signalling system, and more particularly relates to an improved form of rail head bond for use in such signalling systems.

The track rails of a railroad are mechanically held together at their adjoining ends by the usual so-called "fish plates," but this mechanical interconnection is not sufficient to make a good electric connection as required in track circuits. Thus, it is essential to provide electric bond wires of high conductivity between adjoining rails, and these bond wires must be firmly attached to the respective rails with clean metallic contact in order to maintain the resistance to current flow between the rails at a minimum. One general type of bond is known as the rail head bond, which comprises a suitable electric cable having a terminal attached to each end. Shallow holes are drilled in the side of the rail heads, a suitable distance from their adjoining ends so that the bond terminals can be driven into these shallow holes to provide a good electrical connection between the two adjoining rails.

With the usual construction of rail head bonds and the methods of attaching the same to the rails, it is possible, after a short time following their installation, for moisture to creep into the connection and cause corrosion which eventually results in such increased resistance of the connection that there is a failure of the associated track circuit including such bond. When this occurs, it is not only difficult and troublesome to locate the particular bond that is failing, since many times such failure will be of the intermittent character, but under certain conditions such a failure becomes a danger and a hazard to the proper and safe governing of train traffic.

One object of the present invention is to provide a rail head bond of an improved character that will maintain a proper electrical connection between the two rails which it connects over a period of time by maintaining such a tight mechanical connection that moisture cannot creep in and cause corrosion or rusting.

A further object of the invention is to provide a rail head bond that will provide the maximum clearance between the bond and the tops of the rails to avoid damage from dolly trucks or dragging equipment.

A still further object of the invention is to provide a rail head bond which is easily removed from its rails in such a way that it can be reused.

Another object of the invention is to provide a

2

bond which is mechanically strong and immune to the usual displacements and mechanical strains ordinarily encountered with rail head bonds of the usual type.

5 Other objects, purposes, and characteristic features of the invention will be in part obvious from the accompanying drawings, and in part pointed out as the description of the invention progresses.

10 In describing the invention in detail, reference will be made to the accompanying drawings, in which like reference characters designate corresponding parts throughout the several views, and in which:

15 Fig. 1 illustrates two adjoining rails connected by a rail head bond constructed in accordance with the present invention;

Fig. 2 illustrates the bond terminal located in position in a suitable recess in readiness to be sealed in place;

Fig. 3 illustrates a side view of the bond terminal after it has been sealed in position;

Fig. 4 illustrates a top view of the bond terminal after it has been sealed in position;

20 Fig. 5 illustrates a typical punch or sealing tool;

Fig. 6 illustrates a top view of an extracting tool;

Fig. 7 illustrates a side view of the extracting tool;

25 Fig. 8 shows a sectional view of the terminal with the extracting tool in position as viewed on line 8—8 of Fig. 2 where the extracting tool has not been shown;

30 Fig. 9 is a front view of the terminal having the same structure as shown in Fig. 1 but with certain dotted lines and reference characters added thereto for reference purposes;

35 Fig. 10 is an enlarged cross sectional view of the terminal as shown in Fig. 8 but without the extracting tool in position and before the terminal has been expanded by the use of the punch;

40 Fig. 11 is an enlarged cross sectional view the same as shown in Fig. 10 but after the terminal has been expanded;

45 Fig. 12 is an enlarged view of the terminal as shown in Fig. 2;

Fig. 13 is an enlarged view of the terminal as shown in Fig. 3; and

50 Fig. 14 is an enlarged cross sectional view taken on line 14—14 of Fig. 12.

With reference to Fig. 1, it will be seen that two adjoining rails 2 and 3 are connected by the rail head bond of the present invention. These rails 2 and 3 are, of course, in practice

mechanically connected by the usual splice plates and bolts, sometimes called "fish plates," all of which has been omitted from the drawings for the sake of simplicity in the disclosure. Although the bond of the present invention is more particularly intended to be employed as a rail head bond, it should be understood that it can also be employed to provide connections at other locations on the rails such as in the base, if desired.

The bond of the present invention includes two terminals generally designated 4 and 6 which are interconnected by a suitable electric cable 5. This cable 5 may be made of any suitable low resistance wire, but is preferably made of many strands of low resistance but high tensile strength bronze wire forming a rope cable suitable for high electrical conductivity and also being capable of withstanding mechanical flexing over long periods of time without breaking.

The terminals 4 and 6 are, of course, constructed alike and are shown in side views in Figs. 2 and 3 and in a top view in Fig. 4. Each terminal is made of a suitable non-ferrous metal, such as copper or copper base alloy, which has the proper degree of hardness to give the desired elasticity to the metal for reasons presently to be explained. This terminal is provided with a plug portion 7 having straight sides, which plug portion fits, with a very small clearance such as a thousandth of an inch, into a suitable shallow hole in the rail head. This hole may be of any suitable size but it has been found practical to make the hole about one-quarter of an inch deep with a diameter of about three-eighths of an inch. The bottom of the plug portion 7 is shaped to conform with the base of the drilled hole in the rail head which has an angle of approximately 60° with the axis of the hole (see Fig. 2). This construction permits the terminal to have its plug portion 7 easily inserted into the hole in the rail with merely a slight tap or hammer blow to complete its insertion. Since the plug so nearly conforms to the size of the hole with only a slight clearance, this operation of inserting the plug can be performed without the possibility of the plug becoming distorted or having a metal shaving taken off its diameter.

Each bond terminal also includes a hole 8 which has a slight taper and is flat at its base. This hole extends into the terminal and towards the plug to a suitable depth but well above the surface of the rail head even when the plug is fully inserted in its receiving hole as shown in Fig. 2 but before the sealing operation presently to be described. This hole 8 is, of course, so located as to have its center line upon the axis or center line of the plug portion 7. The cross sectional area of the hole 8 is a relatively small percentage of the total cross sectional area of the plug 7, which percentage may be in the order of twenty-five per cent for example.

The lower portion of the terminal 4 includes a projection 9 having a hole 10 for receiving one end of the cable 5 while the other terminal 6 has a similar hole 10 for receiving the other end of the cable 5. These holes 10 are suitably countersunk at both ends for reasons to be presently explained.

Each end of the cable 5 has its strands held tightly together by a suitable tool, and the several strands of each end fused together. These fused ends of the cable 5 are then inserted into the receiving holes 10 of their respective terminals 4 and 6 and are mechanically fastened in place within their terminals by the formation of de-

pressions 11 in the terminal projections 9 as indicated in Fig. 1. Once the cables have been mechanically fastened, the ends are then fused or brazed to their respective terminals forming a cone-shaped portion of solid metal where the cable is attached to the terminals since the holes 10 are suitably countersunk.

Thus, it will be apparent that the indentations 11 act to hold the cable 5 securely within the terminals to insure a good mechanical contact between the cable and its terminals both for the purpose of dissipating heat when the cable is being brazed or welded to its terminals, and also for the purpose of protecting the brazed connection from mechanical vibration during any flexing movement of the cable 5. In this connection, it will be noted that the fixed portion of the cable is actually located at the center line of the terminal because of the indentations 11, so that upon the occurrence of a flexing movement of the cable a certain amount of strand migration may take place even within a portion of the terminal. In other words, the strands are free to move with respect to each other even within the terminals up to the points 11. This permits the strands to start flexing at points 22 (see Fig. 1), and permits their freely flexing at points 23. Since the holes 10 are countersunk on the inner sides of the terminals 4 and 6, this flexing movement of the cable 5 can occur without coming in contact with sharp and square corners on the respective terminals 4 and 6. Also, this organization allows the flexing movement in a manner to have such flexing distributed over the length of the cable to prevent the concentration of such movement at any particular points, such as points 23.

After the plug portion of a terminal has been inserted into its receiving hole in the rail head, the punch or sealing tool 16 of Fig. 5 is inserted in the hole 8 and is given one or more hammer blows as required to cause the expansion of the plug portion to completely fill the hole within the rail head and also to produce an expansive pressure of several hundreds of pounds. This pressure is exerted in all directions as indicated by arrows in Fig. 3, and the hole 8 even after the hammer blows have been applied to the punch does not and should not extend below the surface of the rail head. This means that the pressures developed within the plug portion 7 of the terminal are equally distributed to all portions of the inner surfaces of the hole in the rail. This is especially essential at the outer edge or periphery of the hole indicated at 13 so that no crack or small fissure will be present to allow moisture to enter and cause corrosion of the inner surface of the steel rail. This peripheral expansive pressure would not be present if the hole 8 were to extend below the surface of the rail. It is also advantageous to have the expansive pressure of such a value that the elasticity of the plug member will cause the plug 7 to completely fill the hole still retaining a substantial value of expansive pressure regardless of variations in the size of the hole with respect to the plug due to the difference in the coefficients of expansion of the plug member and during changes in the ambient temperature. It is for this reason that it is desirable to form the terminal of a suitable metal with a proper degree of hardness to give the required elasticity. One suitable metal is a cooper alloy including approximately five per cent tin. The presence of the tin in the alloy increases its tensile strength and hardness, which increases the elasticity of the

metal and acts to maintain the expansive pressures under varying ambient temperatures.

The presence of substantial expansive pressures against the walls of the hole in the rail at all times also serves to protect the hole from certain mechanical deformations due to the impact received by the sudden entrance of a train wheel on one rail as it leaves the other rail. This sudden impact would cause a deformity in the hole receiving the plug, especially at the lip or outer edge of the hole, if there was insufficient support near the periphery of the hole. In the usual bond commonly employed, the expansive force at the outer edge of the hole is insufficient to maintain the hole in its original form during the service of the rail and bond, whereas the bond of the present invention eliminates this difficulty by not allowing a protruding lip to be formed. Such a protruding lip in the usual bond acts to cut into the terminal plug and create a fissure for the entrance of moisture.

With reference to Fig. 1, it will be seen that each terminal is balanced about the centerline or axis of the plug portion; and also, there is equal portions of the cable 5 on opposite sides of a vertical line passing through the plug axis. This balance tends to prevent a turning action as would occur with ordinary unbalanced bonds, when a rail receives the impact of an entering wheel.

As above mentioned, the hole 8 is slightly tapered which permits the entrance of the punch 16 with sufficient clearance to readily allow the point of the punch to reach the seat of the hole in readiness for the hammer blows required to expand the plug portion of the terminal. In this connection, it will be seen that since the hole 8 is only approximately twenty-five per cent of the plug area, any slight deviation in the direction of the punch as it receives its blows will not materially affect the expanding action of the plug member.

With reference to Figs. 1 and 2 it will be seen that the terminals 4 and 6 are provided with chamfered edges as indicated at 14 so as to prevent dragging equipment from readily catching onto the terminals. Since the hole 10 for receiving the cable 5 is in the lower part of the terminal below the plug member 7, it is possible for the upper portion of the terminal to be slanted inwardly towards the top of the rail as viewed in Fig. 2, thus further rendering the terminal less susceptible to dragging equipment. Also, the cable 5 extends downwardly from the head or surface of the rail and thus avoids dragging equipment.

As above mentioned, the cable 5 is brazed at points 12 after extending through the holes 10 in the terminals 4 and 6 which forms cone-shaped metal portions and renders the cable very substantially attached to the terminal since any endwise pull on cable must be against the resistance of the brazed portions to entering into the holes 10. Also, the mechanical denting of the terminal at 11 tends to hold the cable in place. This arrangement insures a strong support for the cable as well as a positive electrical connection between each strand of the cable 5 and its terminals. Since the points of brazing are on the outside of the terminals, they may be readily inspected for any possible defects either in manufacture or in service.

The inner edges of the terminals are slanted as indicated at 15 in Figs. 2 and 4 so as to permit the insertion of an extracting tool 17 without any particular exertion of force. It will be seen in Fig.

6 that the extracting tool 17 is a forked member having wedge-shaped fingers 18 as viewed in Fig. 7. These wedge-shaped fingers fit on each side of the terminal, when an extracting operation is to be performed, with the straight portion of the tool against the rail and the inclined portion against the inclined surface of the terminal. The operator then proceeds to exert pressure on the end of the tool 17 with the head of the rail acting as a fulcrum. With this arrangement, it is seen that the pressure on the terminal is applied at the points 19 on opposite sides of the terminal forming a line intersecting the axis of the plug. This means that the terminal is pulled outwardly in a straight line with the axis of the hole in the rail, because as the plug is removed and the extractor begins to be inclined, the lower surface of the fingers 18 will not come into contact with the lower flat surface of the terminal until the plug has actually been removed. In this way the terminal is maintained intact for further service without in any way harming the attachment of the cable 5 to the terminal.

Fig. 8 is a sectional view of the terminal with the extracting tool 17 having its forked fingers 18 in position. The section is taken on line 8—8 of Fig. 2, in which there is, of course, no extractor shown.

It will be noted that the fingers 18 of the extractor fit the contour of the terminal, and especially the inner sides of the fingers are rounded to fit the curved fillet of the terminal. Thus, as pressure is applied to the extractor with the rail acting as a fulcrum forces are applied to the terminal at points 19 as explained in connection with Fig. 4, but these forces not only have extracting components (i. e. forces perpendicular to the side of the rail and parallel to the axis of the plug portion) but also have components pressing inwardly on the terminal due to the rounding corners of the extractor fingers. The resultant of the forces on the terminal are thus directed slightly toward the axis of the terminal and plug, which effects the pulling or extracting of the plug from its receiving hole in the rail without deforming or shearing the edges of the terminal. This not only permits the reuse of the bond, but by maintaining the bond intact no portion is left in the rail to hinder reuse of the hole when the rail is relocated.

As above mentioned, it will be appreciated that when the wheels of an engine or car approach the leaving end of a rail, that end of the rail drops slowly due to the weight imposed upon it. Assuming the fish plates between adjoining rails to be slightly loose, which often occurs in practice, the entrance of the wheels onto the end of the other rail causes it to be thrust suddenly downward by the impact received from the entering wheels. With reference to Fig. 1, and assuming rail 2 to be the leaving rail and rail 3 to be the entering rail, this sudden impact upon the entering rail gives a turning moment to the respective terminals through the pressures produced on the connecting cable which tends to cause both terminals 4 and 6 to be turned in a clockwise direction. It should also be observed that this sudden impact upon the entering rail and its rapid movement downward is also accompanied by the sudden release of the leaving rail so that it tends to move upwardly rather rapidly. Also, the return of the entering rail to its normal position is a rather slow upward movement.

With reference to Fig. 9, it will be seen, however, that the lever arm of turn resisting moment of the plug portion 7 is represented by the

distance designated 20; whereas, the lever arm of turning moment of the terminal as having pressure applied by the cable is represented by the distance designated 21. It can be seen that the ratio of the distance 20 to distance 21 is kept at a minimum by the location of the cable receiving hole 10 beneath the plug portion. For this reason, the sudden impact and turning moment applied to the terminals is successfully withstood by the bond organization of the present invention. This is especially true since the resistance to turning is increased by reason of the increased compressive pressures within the plug portions of the terminals and also because the ratio of the turning moment on the terminals is kept at a minimum.

In addition to the above reasons, it will be seen that the location of the connection of the cable 5 beneath the terminals provides for a maximum length of cable for flexing movement assuming any given distance between the receiving holes for the plugs of the respective terminals 4 and 6 of Fig. 1. In actual practice, this distance is ordinarily about four inches and a suitable amount of slack in the cable is provided to prevent a pulling action on the cable due to the contraction and expansion of the rails and any relative motion between the rails due to loose plates. This increase in the effective length of the cable gives greater flexibility and reduces the forces due to wheel impact and relative movement of the rails. Thus, all factors considered, the bond of the present invention successfully opposes any turning action and thereby eliminates any resulting pull on the cable. It will also be noted from Fig. 9 as well as from Fig. 2, that the center line of the cable 5 at its ends falls approximately on the circumference of the plug members of the respective terminals. Thus, any pulling action on the cable which may occur has a minimum of turning moment on the two terminals and is successfully opposed not only by the mechanical holding of dents 11 but also by the cone-shaped fused portion of metal at the ends of the cable.

For the convenience of those who wish to consider the exact form of the terminal of the present invention, enlarged views of the terminal as shown in Figs. 2, 3 and 8 have been shown in Figs. 10, 11, 12, 13 and 14. The same reference characters are of course used in these figures. Since these enlarged figures are merely a reproduction of the main figures, it is believed unnecessary to give added detail description, since the description already given applies exactly.

However, it may be well to note that Fig. 10 represents the terminal before expansion; whereas, Fig. 11 represents the terminal after expansion. In both Figs. 2 and 12 the drawing is shown as if the terminal were complete and the rail were cross-sectioned at the centerline of the hole receiving the terminal plug. This is entirely proper since the terminal is not expanded in these figures. On the other hand, Figs. 3 and 13 do not show the rail cross-sectioned because the terminal plug is shown expanded and such expansion resulting in trapped pressures within the plug requires complete confinement of the expanded portion of the terminal plug.

Fig. 14 is a cross sectional view taken on line 14—14 of Fig. 12 for the purpose of illustrating the indentation 11 and its action to hold the cable 5 securely within the terminal to insure a good mechanical contact between the cable and its terminal both for the purpose of dissipating

heat when the cable is being brazed or welded to its terminal and also for the purpose of protecting the brazed connection from the mechanical vibration during any flexing movement of the cable 5. This enlarged figure will make more clear the feature described above wherein the strands of the cable 5 are free to move with respect to each other even within the terminal up to the point 11 for reasons previously described in detail.

Having described a rail head bond as one specific embodiment of the present invention, it is desired to be understood that this form is selected to facilitate in the disclosure of the invention rather than to limit the number of forms which it may assume; and, it is further to be understood that various modifications, adaptations, and alterations may be applied to the specific form shown to meet the requirements of practice, without in any manner departing from the spirit or scope of the present invention except as limited by the appending claims.

What I claim is:

1. In an electrical bond for connecting adjoining track rails, a multiple strand conductor of flexible wire having a terminal attached at each end, each terminal having a solid plug integral therewith and adapted to fit into a receiving hole in a track rail, the terminal having a recess extending through it and partially into the plug, said recess being of relatively small cross-sectional area and in line with the axis of the plug but of a depth insufficient to enter any portion of the plug that is received by the hole in the rail, whereby the insertion of a flat-faced punch into said recess and the imparting of hammer blows to said punch effects the expansion of the plug in all directions within said hole to completely fill its receiving hole in the rail without the recess being extended sufficiently to enter said plug below the surface of the rail.

2. In an electrical bond for connecting two adjoining track rails, each having a receiving hole near its end, two terminals, each having an integral solid plug located in the receiving hole of its respective rail, and expanded therein by an impact against a flat-faced sealing punch producing an indentation in said terminal slightly entering said plug to cause its expansion by the flow of metal within the confines of the receiving hole in the rail, the lower portion of each terminal having a cable receiving extension with its horizontal length equally balanced on opposite sides of the plug axis, and a flexible cable extending between said terminals with a slight amount of slack and with the ends of the cable fused to the respective cable receiving extensions at their outside extremities, said cable receiving extensions completely surrounding the respective cable ends but not binding the cable except at a point in line with said plug axis at which point said cable receiving extension is compressed to bind the cable.

3. In an electrical bond for connecting two adjoining track rails, each having a receiving hole near its end, two terminals, one for each rail, and each having an integral solid plug located in the receiving hole of its respective rail, and expanded therein by an impact against a flat-faced sealing punch producing an indentation in said terminal slightly entering said plug whereby to place said plug under a substantial expansive pressure, a portion of each terminal extending downwardly from said plug and equally positioned on opposite sides of the plug

axis and having a hole extending through the extension parallel to the track rails, a flexible cable extending between said terminals and having its ends passing through the cable receiving holes and extending out of the terminal sufficiently for such ends to be fused to their respective terminals, and a centrally located indentation on each terminal extending portion for causing that terminal to mechanically hold the cable in place.

4. In an electrical bond for connecting two adjoining track rails, each having a receiving hole near its end, two terminals each having an integral solid plug located in the receiving hole of its respective rail, and expanded therein by a compressive impact producing an expansive pressure against all walls of the receiving hole, the lower portion of each terminal extending downwardly and having a hole completely through it for receiving a cable, a flexible cable extending between said two terminals and its ends entering the cable receiving holes of the terminal and having its extreme ends protruding sufficiently to be fused thereto, said terminal having portions on each side protruding away from said plug and slanted inwardly and towards the rail to the center line of said plug for receiving a wedge-shaped forked extractor to be fulcrumed on said rail and contacting the terminal at the axis of said plug to effect an extraction on a line parallel with the axis of the hole in the rail.

5. In a rail bond, an electrical conductor, a terminal integral with a solid plug at each end of the conductor, said conductor being attached to the terminals but being inserted through a hole in each terminal parallel with the bottom edge of its terminal and below the center line of the plug, the conductor being mechanically secured to the terminal by forming an indentation at the bottom edge of the terminal at its center line which is effective to compress the cable within the terminal against the sides of the hole, and electrically secured to the terminal by welding the extreme end of the cable to the side of the terminal.

6. In a rail head type signal bond, a terminal integral with a solid plug of relatively high tensile strength non-ferrous metal at each end of a flexible conductor, said conductor consisting of many strands of bronze wire wound in the form of a rope cable, each of said terminals completely encasing its end of said cable and holding the cable beneath the associated plug with the extreme end of the cable welded to the terminal, which terminal mechanically secures said cable at the center line of its plug by a compressed portion although still allowing the strands of said cable to migrate in the remaining portion of the terminal, two adjoining rails connected by splice bars, a hole of a predetermined depth in each rail end for receiving the plug of its respective one of said terminals, each of said plugs being of a proper length greater than said predetermined depth of said hole to allow said terminal to be away from the rail surface a proper amount to amply clear protruding splice bars.

7. A rail head plug type signal bond, having a solid plug and cable terminal in one piece of homogeneous non-ferrous metal of high tensile strength, having a recess extending through the terminal on the axis of the plug, the diameter of the recess being about one-half the diameter of the plug but not entering the plug, the face of the terminal above the cable being tapered so

that the open end of the recess will be oblique, the bottom of the opening extending out beyond the top so as to form a shelf thereby making it easy to insert a punch.

5. In combination, a rail head having a bottomed hole in its side of the dimensions used for installing a signal bond of the plug type, a signal track circuit bond having a solid plug and terminal of one homogeneous piece of high tensile strength non-ferrous metal, the plug being inserted in a rail hole with a narrow space between the terminal and the rail, the terminal having a recess which is in line with the axis of the plug into which the flat end of a hardened steel punch is inserted, the opposite end of the punch being struck sufficient blows to shear metal below the recess in line with the axis of the plug on a circumference slightly smaller than the diameter of the recess and compress the metal longitudinally with the axis of the plug until the compression in the plug causes it to expand radially to seal the periphery of the hole in the rail, the punch then being removed, the cross-section through which the punch sheared having a greater tensile strength than the pull required to extract the plug from the hole in the rail, and a forked extractor adapted to fit into said space between the rail and the terminal for prying said plug from the hole in the rail head.

9. In a rail head electrical signal bond, a conductor, a terminal integral with a solid plug attached to each end of said conductor, each terminal and plug being a drop forging of non-ferrous metal, each terminal having a small recess in axial alignment with its plug for guiding a sealing punch, the recess having a cross-sectional area approximately twenty-five percent of the cross-sectional-area of plug, and only a few thousandths of an inch larger than the diameter of the punch, each terminal being substantially flush with plug circumference at the top, but extending below the recess, the bottom of the terminal being horizontal and rounded, the terminal extension having a hole extending its entire length parallel with the rail head, each end of the hole being counterbored, said conductor being attached to the terminals through the holes in the terminal, the conductor consisting of many strands of flexible bronze wire wound in the form of a rope cable, each end of the conductor being brazed to the side of the terminal forming a cone shaped section on end of conductor to secure an electrical contact and in addition prevent cable from being pulled out, the unsupported section of said conductor being a single drop loop entirely below the punch recess in the terminal, the conductor being formed over three radii so as to distribute the flexing of the conductor.

10. In a rail head type signal bond, a terminal integral with a solid plug of relatively high tensile strength non-ferrous metal at each end of a flexible conductor, said conductor consisting of many strands of bronze wire wound in the form of a rope cable, each of said terminals completely encasing its end of said cable and holding the cable beneath the associated plug with the terminal mechanically securing said cable at the center line of its plug by a compressed portion although still allowing the strands of said cable to migrate in that remaining portion of the terminal which encases the cable extending to the other terminal, two adjoining rails, a hole in each rail for receiving the plug of its respective one of said terminals, and a centering recess in each of said terminals on the axis of its plug

11

for allowing a flat-faced punch to be positioned in line with the axis of said plug whereby one or more hammer blows on said punch serves to shear small portions of said terminal to expand said plug inside its hole in the rail without extending said recess into such hole.

11. In a rail head bond, a terminal adapted to be attached to a rail head and having a connection to a multiple strand cable comprising an enlarged portion of said terminal extending to one side thereof and having a cylindrical hole passing there-through, a multiple strand cable having one end passed through said hole, said one end of the cable being brazed to the side of said enlarged portion, and a deformation in said enlarged portion of said terminal at an intermediate point of said cylindrical hole to constitute a fixed mechanical anchorage for said cable within said hole, whereby movement of the free portion of said cable relative to said terminal is ineffective to cause any substantial flexing of the cable immediately adjacent its anchorage within said cylindrical hole although a limited strand migration is permitted.

12. In a rail head bond, a terminal having an enlarged portion, a cylindrical hole passing through said enlarged portion of said terminal, a multiple stranded cable passing through said cylindrical hole, an indentation of said enlarged portion at a mid-point along the longitudinal length of said cylindrical hole for mechanically anchoring said cable within said terminal, and means located to one side of said mechanical anchorage for electrically connecting said cable to said terminal, whereby lateral flexing excursions of the free portion of said cable on the other side of said mechanical anchorage results in a limited longitudinal migration of the strands of said cable within said cylindrical hole without any substantial lateral flexing adjacent said mechanical anchorage.

13. In a rail head bond, a terminal having a solid plug of relatively high tensile strength non-ferrous metal adapted to fit into a hole within a rail, said plug being of a depth less than the length of said plug, a recess in the face of said terminal in line with the axis of said plug and of a depth insufficient to enter any portion of said plug received by the hole in the rail, said recess having a relatively small cross-sectional area compared to the cross-sectional area of said plug, whereby the insertion of a flat-faced punch against the bottom of said recess with several hammer blows internally shears small portions of said terminal to effect the expansion of said plug within the hole beginning at its base to completely fill said hole in the rail and create a continuing expansive pressure against the side walls of said hole in the rail without any substantial expansion of that portion of said plug outside of said hole and with the base of said recess in said terminal still being above the surface of the rail.

14. In a rail head bond, a terminal having an integral solid plug adapted to fit into a hole within a rail, said hole being of a depth less than the length of said plug to thereby provide a small space between said terminal and the surface of the rail, a recess in said terminal in axial alignment with said plug of a depth insufficient to enter any portion of said plug, whereby the application of several impacts on the outer end of a punch having its small flat-faced end inserted

12

against the bottom of said recess causes the extension of said recess by shearing action to effect the expansion of said plug from the bottom of the hole outwardly until the entire hole in the rail is sealed without any substantial expansion of that portion of said plug outside of said hole and with said recess still of a depth insufficient to enter that portion of said plug which is inside of said hole, a portion of said terminal extending below the circumference of said plug and on its opposite sides, said portion having a horizontal cylindrical hole passing through it, a cable having one end passed through said cylindrical hole and electrically attached to one side of said portion, and an indentation at a mid-point of said portion to constrict said cylindrical hole to constitute a mechanical anchorage for said cable, whereby movement of the free portion of said cable relative to said terminal is ineffective to cause any substantial flexing of said cable adjacent its anchorage and is also ineffective to cause any turning action of said plug on its axis because the high expansive pressure between said plug and the rail head is capable of resisting the turning moments of force since they are reduced to a minimum by reason of the extending portion of said terminal being located on opposite sides of said plug.

15. In a bond for electrically connecting two adjoining rail ends, a hole in the head of each rail near its end, two terminals, one for each rail, and each terminal having an integral solid plug adapted to fit into the hole of its associated rail and be expanded therein by the driving of a flat-faced punch on the axis of said plug to shear an indentation without entering said plug below the surface of the rail, an enlarged portion of each terminal extending below the circumference of said plug and having a horizontal cylindrical hole passing through such portion, a length of cable extending between said two terminals and having each end being passed through the cylindrical hole of the corresponding terminal and brased to the terminal, and each terminal having an indentation of said enlarged portion at an intermediate point along the length of said cylindrical hole to constrict the sides of such hole against said cable to provide a mechanical anchorage for said cable within the hole, whereby any transverse relative motion between said rails causes flexing of the free portion of said cable without causing flexing adjacent its points of anchorage in said terminals and causes a minimum of turning force on said terminals which is effectively resisted by the two terminals by reason of the high expansive pressures of their respective plugs against the walls of the holes in said rails.

HARRY H. SEIFERT.
